Claims priority, application Japan Dec. 29, 1961

8 Claims. (Cl. 343—752)

This invention relates to an antenna for radio and television reception, and more specifically concerns a new antenna of improved compact design that may be readily tuned to different wave lengths and which is particularly useful in connection with receiving devices operating on ultra-short ranges.

A large variety of different types of antennas commercially available are adapted to serve specific requirements of receiving devices. It has been found, however, particularly in the field of indoor antennas, that improved performance generally required the inclusion of large antenna members and extensions, which are awkward and require considerable space. On the other hand, past efforts to develop more compact designs usually resulted in reduced performance, and adjustment to the reception of a variety of wave lengths became difficult.

This invention has as one of its objectives the provision of an efficient indoor antenna for short-wave devices which takes up a minimum of space and which is light and easily transported.

Another objective of this invention resides in the provision of a short-wave antenna which is easily tuned to a selected frequency and will hold the adjustment until tuned to another frequency.

A further objective of this particular invention resides in the provision of an improved organization and arrangement of antenna components wherein the receiving elements may be adjusted simultaneously for maximum reception at a specific wave length.

A still further objective of this invention entails the provision of a smaller indoor antenna characterized by a relatively simple design and structure which may be easily mass-produced at very low cost.

A further objective of this invention resides in the provision of an improved adjustable antenna that is readily adaptable for use over a wide range of frequencies.

The above and additional objectives and advantages will become more apparent from the following description and drawings forming part of this application.

In the drawings:

FIG. 1 is a perspective view of the embodiment of this invention.

FIG. 2 is a cross-sectional illustration showing all internal details of the antenna shown in FIG. 1.

FIG. 3 is an enlarged perspective view of the upper portion of the antenna showing the contacts of the antenna lead connected to both of the end portions of the antenna arms.

FIG. 4 is a plane view of the antenna taken from FIG. 2 at the line 4—4 thereof.

FIG. 5 is a cross section of the supporting neck of the antenna taken from FIG. 2 at the line 5—5 thereof.

FIG. 6 is a side view of the apparatus shown in FIG. 1.

FIG. 7 is a cross-sectional illustration of a modified circuit provided with an alternate knob for the antenna.

Broadly, this invention contemplates the provision of an ultra short-wave antenna requiring considerably less space than known antennas, and one which may be easily and manually tuned over a relatively wide frequency range.

These advantages and objectives are attained through a novel and improved design of a main support for an

2

antenna in combination with improved flexible, U-shaped receiving members each having one end attached to the support and the other end slidably engaging channels within the support, and extending outwardly therefrom in parallel relationship for attachment of a knob or handle. Such an arrangement facilitates adjustment of the antenna to a position affording the best reception for a selected wave length by increasing or decreasing the length of the arcuate receiving members extending from the antenna support.

To adjust the frequency of the antenna, the knob or handle is pushed toward the support attached thereto, to expand the flexible members outwardly and away from the supporting base and thereby decrease the frequency. Conversely, when the knob is pulled upwardly away from the support, the length of the arcuate receiving members is shortened, thereby effecting normally increased efficiency in shorter wave length ranges.

In addition to the high efficiency obtained by this antenna, the simplicity of its design, and the practicality of its operation, it is marked by a pleasing appearance and by a compactness which makes this antenna extremely useful, especially for indoor operations.

Referring now to the drawings and specifically to FIG. 1, the supporting member 10 of the antenna is stabilized by and secured to a hollow metal base plate 11 having open lateral sides and an opening in the rear where the connecting cable 12 enters the base. The base plate is relatively heavy in relationship to the structure mounted thereon to stabilize the apparatus. This is especially important while the receiving members are extended completely. The base plate is preferably made out of a metal, while the supporting structure of the antenna could be constructed of a lighter material such as durable plastic or similar material, providing insulation for the antenna members secured thereto and carried therein. The upright supporting member 10 has two spaced parallel plane surfaces, while the outer periphery describes a symmetrical vase-like configuration with outwardly extending supporting brackets 13 and 14 on the uppermost portion and similar brackets 23 and 24 at the lowermost portion.

The upper brackets 13 and 14 each carry one leg of the U-shaped receiving members 15 and 16, the latter being secured by means of screws 17 and 18 extending through brackets 13 and 14 and receiving members 15 and 16 and threadably engaging square plates 19 and 20 to securely fasten the receiving members to the brackets of the supporting base.

These flexible receiving members are preferably made of a highly flexible steel tape, such as is used in conventional retractable tape measures and might be plated with a coating of nickel or chrome to prevent oxidation of the surfaces. As may be observed in FIG. 5, these receiving members prescribe a slightly curved configuration in their cross section. The curvature across the width of the tape offers additional longitudinal strength required to keep the tape from becoming recumbent when extended beyond the configuration of the arc prescribed.

The flexible receiving members 15 and 16 extend away from the supporting base in opposite directions, prescribing semi-circular arcs 21 and 22 respectively. The lower or return legs enter the support 10 through channels within the support which open in the ends of brackets 23 and 24.

There are three separate channels within the support which are insulated from each other. Channels 25 and 26 have side openings 15' and 16' in the ends of supporting brackets 23 and 24 and extend inwardly describing an upwardly curved course leading to individual openings in the top surface of the support. A third channel 12'

extends vertically between channels 25 and 26 and carries the cable 12. A magnified cross section of the guiding channels within the support is provided by FIG. 5 which is a cross section taken at the line 5-5 from FIG. 2. The return legs of the U-shaped receiving members 15 and 16 are slidably carried in the channels 25 and 26 with the ends of these extending vertically and parallel to each other beyond the top of the support. These free ends of the receiving members are secured to each other by a bolt 28 and a nut 29 within the knob 27, providing the necessary contact therebetween.

The knob 27 facilitates manual control of the length of the legs of the U-shaped receiving antenna members with the weight of the knob counterbalancing the tension exerted by these members so as to retain the arcs in any selected position, which will not be displaced by vibratory or other external forces.

A better insight into the functional elements of this antenna is provided by FIG. 2. When downward pressure is exerted on the operating knob 27, the steel tapes are forced downwardly within the channels 15' and 16' provided within the supporting member 10 and emerge on opposite sides of the support, increasing the lower legs of the U-shaped members, while the other ends of the tape remain fixedly secured to the brackets 19 and 20.

Referring now to FIG. 6, the insulated antenna lead 12 enters the base through an opening 32 in the base and extends upwardly through channel 12' within the support 10. The ends 30 and 31 of this lead emerge from an opening near the top of the support 10 where the stripped leads are soldered or otherwise secured to the plates 19 and 20 as may be readily observed in the enlarged illustration of FIG. 3.

Although any convenient means for mounting the support on the hollow metal base may be utilized, FIG. 2 shows one procedure which utilizes an interlocking tongue and groove arrangement at 33 on one side of the support, while the opposite side of that support is provided with a spring-operated locking arrangement, comprising a spring 34 secured to the support and extending downwardly in a recess 35 to engage cooperating means on the base. In this manner, the support 10 and the base 11 can be easily disengaged by exerting pressure on the lower portion 36 of spring 34 to release it from engagement with the base.

A modification of the invention is illustrated in FIG. 7. In this form, a hollow knob 37 receives the ends of the receiving members 15 and 16 which are secured to an insulator 38 by screws 39 and 40 threadably imbedded in said insulator. A coil 41 within the knob 37 connects the two antenna members one to the other and thereby lowers the frequency range of the antenna. The knob is secured in position enclosing the coil 41 and the ends of the antenna elements by means of a bolt 42.

The latter modification in combination with the antenna described makes this invention an efficient and most versatile apparatus having a relatively wide frequency range. The design is also characterized by its simplicity, compactness and relatively low cost.

While only certain embodiments of this invention have been illustrated and described in the application, it is apparent that alterations and modifications may be made without departing from the true scope and spirit thereof.

What is claimed is:

1. An antenna comprising a support, U-shaped flexible receiving elements each having one leg secured to said support and extending outwardly therefrom, said sup-

port including a pair of channels extending therethrough and slidably receiving the other legs of said receiving elements with the ends of the last said legs extending from said channels, means carried by the ends of said other legs for movement toward and away from said support to adjust the length of said elements, and means on said antenna for attachment of an antenna cable thereto.

2. An antenna according to claim 1 wherein said flexible receiving elements are formed of steel tape having a slight cross-sectional curvature for additional stiffness and resilience.

3. An antenna according to claim 1 wherein said knob is weighted to counterbalance the pressure exerted against said knob by the resilience of said receiving elements.

4. An antenna according to claim 1 wherein a coil connects two corresponding ends of said receiving elements, and said antenna cable means is connected to the other corresponding ends of said elements.

5. An antenna according to claim 1 wherein each of said channels extending through said support has one opening on one side of said support, said channels leading inwardly from their respective openings, curving upwardly within said support, and terminating in the top surface of said support and each of said channels slidably carrying a leg of said receiving element.

6. An antenna according to claim 1, wherein the support has insulating characteristics and has a vertical channel carrying a connecting cable.

7. An antenna for receiving devices, comprising a stabilizing base, an upright support secured to said base, at least two flexible, U-shaped receiving elements carried by said support with said receiving elements extending from opposite surfaces of said support, each element having one leg secured to opposing surfaces of said support, and being insulated from each other by said support, said support having channels therein, said channels each having an opening on said opposing surfaces and in a plane defined by said legs secured to said support, said channels extending from said openings inwardly and curving upwardly to openings in a surface intermediate to said side surfaces, the other leg of each of said U-shaped receiving elements being slidably carried each within one of said channels, the free ends of the last said legs extending at equal length and in parallel relationship each from the said last openings, an electrical connection between said ends, a nonconductive knob securing said ends one to the other, said support including another channel extending vertically through said support and an insulated connecting cable therein, said cable including two terminals, said terminals being electrically connected to said first legs and said cable providing means for attachment to a receiving device.

8. An antenna according to claim 7 wherein the first said electrical connection comprises a coil connected between said ends of said receiving elements and disposed within said knob.
